UNITED STATES PATENT OFFICE

1,962,843

CASTING MACHINE

Walter J. Rudolph, Chicago, Ill., assignor to Ludlow Typograph Company, Chicago, Ill., a corporation of Illinois

Application February 26, 1932, Serial No. 595,393

8 Claims. (Cl. 22—70)

My invention relates more particularly to improvements in machines for casting slugs, or the like, used in printing operations and comprising, generally stated, a crucible, or casting-pot, forming the supply of the molten metal from which the slugs or the like are to be cast, and a mold to which the molten metal is supplied; the invention relating, as by way of example, and more particularly, to machines of the general type shown in United States Letters Patent No. 1,124,293 granted to E. S. Carman, January 12, 1915, in which machine the crucible is supported to rock about a horizontal axis and to swing about a more or less vertical axis and is associated with means for pumping the molten metal through the outlet of its throat portion, the machine also comprising a matrix structure supported against upward movement and a vertically movable mold the cavity of which opens through both its upper and lower surfaces, the machine operating to lift the mold to engage the underside of the matrix structure, thereafter swing the crucible to a position in which its throat portion is directly below the mold and then raise the throat portion into engagement with the bottom of the mold, the pump then being operated to force a charge of molten metal from the crucible into the mold. Following the operation just stated the crucible swings horizontally across the bottom of the mold and to one side thereof and then rocks downwardly at its throat portion away from the mold, the metal at the underside of the mold is trimmed off and the mold lowers to a position in which the cast slug is ejected.

My objects, generally stated, are to provide improvements in machines of the general character above referred to the end that the amount of air required to be displaced by the molten metal in the casting operation will be reduced to the minimum; that such air as is in the mold may be displaced freely by the molten metal and thus permit of the making of a perfect cast; that the metal will flow into the mold in a flat stream as distinguished from the jetting of the metal into the mold through a series of small openings; and that the mouthpiece, or "squirt" plate provided at the throat portion of the crucible will be maintained at all times substantially at the same temperature as the molten metal and thus avoid freezing of the metal in the mouthpiece during the intervals between the casting operations; and other objects as will be manifest from the following description.

Referring to the accompanying drawings:

Figure 1 is a fragmentary view in side elevation, with certain parts sectioned, of a casting machine of the general construction, and operating on the same principle, as that shown in said Letters Patent, the mouthpiece of which is constructed in accordance with my invention.

Figure 2 is an enlarged detailed sectional view of a portion of the structure shown in Fig. 1.

Figure 3 is a plan view of the crucible of Fig. 1.

Figure 4 is a vertical sectional view taken at the line 4—4 on Fig. 3 and viewed in the direction of the arrows.

Figure 5 is a plan view of the mouthpiece.

Figure 6 is a view in side elevation of the mouthpiece.

Figure 7 is an end view of the mouthpiece; and

Figure 8, a broken view in vertical section of the mouthpiece showing it in operative position relative to the mold.

Referring to the particular construction of casting machine illustrated and in connection with which I have chosen to illustrate my invention, 9 is the crucible, or casting pot, of the machine commonly heated in any suitable way to maintain therein a supply of molten type metal and mounted in a supporting casing 10, the crucible 9 comprising a reservoir portion 11 and a throat portion 12 having a separate mouthpiece 13, the reservoir portion 11 being provided with means for forcing the metal therefrom through the throat portion 12 and into a mold hereinafter referred to, these means being shown as formed of a cylindrical well 14 in the reservoir portion 11 opening at its lower end into the throat portion 12 and at a port 15 into the reservoir portion 11 and a piston 16 reciprocable in the well 14 and operated by mechanism comprising the links 17.

18 represents the bed plate of the machine shown as disposed in slanting position and containing an opening 19 over which a set of matrices 20 supported in a "stick", to cast the desired line composition on the slug to be formed, is positioned and held against vertical displacement.

The mold of the machine is represented at 21 and is open top and bottom and supported to be moved vertically into and out of the position shown in Figs. 1 and 2 wherein it fits at its upper portion against the underside of the matrices 20 which latter form the top of the mold.

The casing 10, carrying the crucible 9, is hinged at 22 to a rotatable pivot member 23, to rock about a horizontal axis, the pivot member 23 being rotatable about a more or less vertical axis, these parts having associated therewith mechanism as described in said Letters Patent for rocking and

70

80

85

90

95

100

105

110

swinging the casing 10, and with it the crucible 9, in such a way that after the mold 21 is moved into engagement with the matrices 20 as shown, the casing 10, with the crucible 9, tilts upwardly 5 to engage the upper surface of the mouthpiece 13 with the underside of the mold 21 and after the casting operation the casing 10 and crucible are swung laterally away from the mold 21 producing a shearing action on the metal at the joint between the mouthpiece 13 and the mold, the casing 10 and crucible structure thereafter rocking downwardly a few degrees from the position shown in Fig. 1.

It may be stated that the particular construction of mechanism illustrated and above described is not of the essence of my invention, this particular construction being shown merely to illustrate one form of machine in which the invention may be utilized; and as this machine as to 15 its general features of construction, and principle of operation, is the same as that shown in said Letters Patent, the foregoing brief description of the machine and its operation will suffice.

Referring now to the particular portion of the machine to which my invention relates, it pertains to the structure at the outlet of the throat portion 12 and more specifically to the construction of the mouthpiece 13.

In accordance with the preferred illustrated embodiment of my invention, the mouthpiece 13 which is formed of heat conducting material, such as for example steel, comprises a platelike portion 24 at which it is adapted to fit against the upper surface of the outlet of the throat portion 12 and be secured thereto as by screws 25 extending through openings 26 in the mouthpiece and screwing into the wall of the throat portion.

The mouthpiece 13 also comprises a fin portion 27 depending from the plate portion 24 and disposed inwardly of the surrounding edges of the plate portion 24, this fin portion extending downwardly into the outlet of the throat portion 12 to be in contact with the molten metal during the periods when the crucible is tilted down from the position shown in Fig. 1, namely, between casting operations, and preferably in contact with the molten metal at all times.

The mouthpiece 13 contains a passage represented at 28 which opens through the bottom of the fin 27 and through the upper surface of the mouthpiece, and through which the molten metal is forced, to enter the mold 21, upon actuating the piston 16.

The side walls of the passage 28, which is relatively long and narrow as shown, flare in a cross-wise direction downwardly from a point approximately midway between the upper and lower surfaces of the plate portion 24 and the bottom of the fin portion 27 as represented in Figs. 4 and 8, the portions of the walls of the passage 28 above the downwardly flaring portion thereof being substantially parallel.

As the fin in the particular construction shown is of wedge shape to adapt it to fit into a throat portion of a crucible of a casting machine as commonly provided, and the opening from the mouthpiece to the mold by preference is of a length substantially equal to the length of the mold cavity, the passage 28 upwardly flares in a direction lengthwise thereof from the lower end of the fin to the outlet portion of the mouthpiece, as shown in Figs. 1, 2 and 6. It will be understood, however, that the shape of the passage 28 may be varied, as desired, from that shown within the scope of my invention.

The outlet of the mouthpiece and through which the metal is forced into the mold 21 is thus in the form of an elongated slot, shown as of substantially the same length as the cavity in the mold, but of a width, as represented in Fig. 4, considerably less than the width of the mold cavity.

One of the purposes of the invention being to provide for the effective conduction of the heat of the molten metal to the outlet of the mouthpiece to the end of maintaining the latter at a temperature as close as possible to that of the molten metal, it is preferred that the fin portion 27 be integral with the plate portion 24 of the mouthpiece thereby to afford the greater adaptability of the structure for the conduction of heat. In the particular construction shown the mouthpiece is formed of two sections 29 and 30 each comprising a part of the plate portion 24 and half of the fin portion 27, these sections fitting flatwise together and forming a joint therebetween represented at 31 which extends lengthwise of the passage 28 as shown in Fig. 5, the sections being represented as held together by rivets 32 engaging the sections of the fin 27 and rivets 33 engaging the sections of the plate portion 24, it thus being understood that each section 29 and 30 formed as a one-piece structure comprises a part of the plate portion 24 and a part of the fin portion 27.

As will be understood, the molten metal does not extend at all times to the upper surface of the mouthpiece, and thus in the forcing of the molten metal through the latter to effect a cast, such air as may be contained between the upper surface of the mouthpiece and the level of the molten metal in the throat portion at the time the cast is to be made, must be displaced by the molten metal. Manifestly it is preferred that the air to be displaced as stated be of the minimum volume, applicant accomplishing this by providing a member which in the particular construction shown is the fin of the mouthpiece, which extends into the throat portion and affords a molten-metal-passage of greatly reduced cross-sectional area as compared with the cross-sectional area of the throat portion 12, the reduction in the cross-sectional area of the molten-metal-passage presenting the further advantage of reducing the area of molten metal exposed to the oxidizing effect of the atmosphere.

The fin in the particular construction shown, wherein it is provided as an integral part of the mouthpiece, thus not only serves to present a passage of relatively small cross-sectional dimensions for the molten metal with the advantages above noted, but serves to conduct heat from the molten metal to the plate portion of the mouthpiece for maintaining this plate portion in heated condition.

The provision of the outlet of the mouthpiece in the form of an elongated slot as stated is of advantage as it permits of the discharge of the molten metal into the mold in the form of a relatively thin sheet as distinguished from jetting the metal into the mold through a plurality of relatively small openings.

It is also desirable in casting apparatus of the general character herein referred to that means be provided for permitting of the escape from the mold cavity, during the casting operation, of the air normally contained therein and such additional air as may be forced into the mold ahead of the molten metal. Accordingly, means are provided for thus venting the mold,

these means according to the particular illustrated embodiment of the invention comprising two series of grooves 34 provided in the upper surface of the mouthpiece at opposite sides of 5 the passage 28 and out of communication with the latter, the inner ends of these grooves registering with the cavity in the mold 21 and their outer ends opening to the atmosphere as shown in Figs. 5, 6 and 8 whereby the air in the mold 10 is vented through a plurality of relatively small openings to the atmosphere, the portion of the mouthpiece through which the upper end of the passage 28 opens and in which the grooves 34 are provided, and represented at 35, being preferably elevated above the plane of the surrounding portion of the mouthpiece as represented in 15 Figs. 5-8 which makes for simplicity of structure as regards the opening of the outer ends of the grooves 34 to the atmosphere.

20 While I have illustrated and described a particular embodiment of my invention, and shown it as incorporated in a particular construction of casting machine, I do not wish to be understood as intending to limit it thereto as the construction may be variously modified and altered and incorporated in other constructions of casting machines without departing from the spirit of my invention.

What I claim as new, and desire to secure by 30 Letters Patent, is:

1. A mouthpiece for the outlet portion of a crucible comprising a portion adapted to form a cover for said outlet portion and containing an elongated discharge slot, portions of the inner 35 surfaces of the walls of which flare laterally outwardly crosswise of the slot toward the inlet portion of said slot.

2. A mouthpiece for the outlet portion of a crucible comprising a portion adapted to form 40 a cover for said outlet portion and containing an elongated discharge slot, the inner surfaces of the portions of the walls of said slot at the outlet portion of the slot being substantially parallel and the inner surfaces of the portions thereof 45 at the inlet portion of said slot flaring laterally outwardly cross-wise of the slot toward the inlet portion of the slot.

3. A mouthpiece for the outlet portion of a

crucible comprising an apertured portion adapted to form a cover for said outlet portion and a hollow passage-forming member projecting from said cover at its inlet side and adapted to extend into said outlet portion and having an opening the walls of which surround the apertured portion of said cover and also an opening for communication with the metal in said outlet portion.

4. A mouthpiece for the outlet portion of a crucible comprising a portion adapted to form a cover for said outlet portion and containing an elongated discharge slot and a hollow passage-forming member projecting from said cover at its inlet side and adapted to extend into said outlet portion and having an opening the walls of which surround said slot and also an opening for communication with the metal in said outlet portion.

5. A mouthpiece for the outlet, throat, portion of a crucible, adapted to extend into said throat portion and comprising flatwise opposed sections together forming an elongated opening through the mouthpiece with the joint between said sections extending lengthwise of the opening whereby the material of the mouthpiece extends continuously, without interruption, from the inlet to the outlet of the mouthpiece.

6. A mouthpiece for the outlet portion of a crucible adapted to extend into said outlet portion and having an elongated slot extending therethrough for the discharge of the molten metal, the inner surfaces of the end walls of said slot flaring outwardly to the extremity of the outlet portion of said slot.

7. A mouthpiece for the outlet of a crucible comprising a portion adapted to form a cover for said outlet and containing a discharge opening, and a wall on said cover portion extending around said discharge opening having a portion spaced laterally from an interior wall of said outlet.

8. In a crucible having a mouthpiece in its mouth, said mouthpiece having a discharge opening therethrough, a wall on said mouthpiece surrounding said discharge opening and depending into said mouth, a portion of said wall being laterally spaced from an interior wall of the mouth and adapted to enter molten metal in the mouth.
